UNITED STATES PATENT OFFICE

EVAN GEORGE WILSON, OF WATERLOO, NEAR LIVERPOOL, ENGLAND

MACHINE FOR ROLLING AND FINISHING LEATHER

Application filed June 18, 1928. Serial No. 286,381.

This invention relates to machines for rolling and finishing skins, such, for instance, as butts, bends, sides, or whole hides of leather, and like materials, of the type which comprises or includes a rolling carriage operatively associated with a guide rail, or the like, and provided with a roller or rollers; mechanical means whereby reciprocatory motion is imparted to said rolling carriage; a horizontal bed or table situated below said rolling carriage and formed of two or more sections; and springs or weighted levers, or the like, whereby said bed or table may be normally maintained in contact with said rolling carriage, and lowered in relation thereto in order to permit material to be positioned on or removed from the bed or table.

In this type of machine the sections forming the bed or table are mounted on separate fulcra which are connected to each other and in turn carried upon a common pivot so that the sections may jointly and independently oscillate during the rolling and finishing operation to compensate for inequalities in the material and to ensure the imposition of a uniform pressure over the whole surface of the material, but in practice it is found that the sections have a tendency to part somewhat as also to ride over each other with the result that the material is marked or scored and sometimes completely severed.

A rolling and finishing machine, according to my invention, has for its main object to obviate the aforementioned defects, and is essentially characterized by the association with the sections forming the bed or table of resilient or flexible means—such as springs—and plates or buffer pieces, by the aid of which springs and plates or buffer pieces said sections are maintained in their correct relative positions and in constant abutment or contact, in order that they may jointly or independently oscillate without parting or over-riding and so that a uniform or level bed surface may be normally presented to material to be treated.

Another feature of my invention, is the provision of adjustable means, substantially as hereinafter described, whereby the rolling

carriage is positively maintained in operative engagement or association with a guide rail, or the like, and is prevented from twisting or angular movement in relation thereto.

Another feature of my invention is the provision of means, substantially as herein-after described, whereby the pressure of said bed or table on the rolling carriage may be varied at will in order that materials of different kinds or grades may be dealt with.

Other and additional features or characteristics of my invention are hereinafter described and pointed out in the claiming clauses concluding this specification.

I will further describe my invention with the aid of the accompanying sheet of explanatory drawings which illustrate, by way of example only, one mode of carrying same into effect.

In said drawings:

Figs. 1 and 1^a show, in side elevation, a rolling and finishing machine constructed in accordance with the invention.

Figs. 2 and 2^a show, in inverted plan, the bed or table, and Fig. 3 is a transverse section of the bed. Figs. 4 to 9, inclusive, show the parts which oscillatably support the bed at each end, Figs. 4 and 5 being views of the fulcrum blocks which carry the bed sections, Figs. 6 and 7 being views of the yoke which carries the fulcrum blocks, and Figs. 8 and 9 being views of the member which centrally supports the yoke.

Fig. 10 shows in section the method of supporting the rolling carriage.

Figs. 11 and 12 are views of the tappets or cams which control the operation or movement of the rolling carriage, and Fig. 13 illustrates the lever mechanism associated with the tappets or cams.

Fig. 14 is a view of a device which facilitates the placing of the carriage mechanism in its neutral position and so stopping the rolling carriage.

1 generally designates the framework of the machine of which 2 are the supports or uprights, and 3 is the horizontal guide rail which bridges said supports 2 and maintains the same in suitably spaced relationship.

Suspended from said guide rail 3 by means of a bracket 4 and a spring-pressed shoe 5 is a rolling carriage 6 provided with a roller 7 revolubly mounted on a spindle 8 and with small grooved wheels 9.

Said shoe 5 which operates in a groove or channel 10 formed in the upper face of rail 3, maintains the grooved wheels 9 in engagement with a feather 3^a formed on the under-side of the guide rail and thereby prevents twisting or angular movement of carriage 6. Screwed into bracket 4 is a sleeve 11 fitted with a screw-threaded handle rod 12, said sleeve and rod being vertically adjustable so as to regulate the pressure of a spring 13 on shoe 5 and to compensate for wear or inaccuracy of the several parts.

Mounted on one of the supports 2 of the machine is a suitable rolling carriage operating mechanism consisting of a fast driving pulley 14, two loose pulleys 15, and a pinion 16 all mounted on a driving shaft 17; a gear wheel 18 fixed to a shaft 19 and meshing with said pinion 16; a pinion 20 mounted on said shaft 19 and meshing with a gear wheel 21 attached to a shaft 22; and a sprocket wheel 23 which is secured to said shaft 22 and is adapted to operate a chain 24, said chain being fixed at each end of carriage 6 and passed over a loose jockey pulley 25 mounted on one of the supports 2, said sprocket wheel 23, and a large jockey pulley 26 mounted on the other of the supports 2.

Mounted in bearings 27 fixed to rail 3 is a spindle 28 which is connected by means of links 29 with a lever 30, said lever being pivoted at 31 and the lower end whereof engages a belt-shifting bar 32. Provided on said spindle 28 are suitably shaped tappets or cams 33, and fixed to the roller carriage 6 are two inclined surfaces 34.

The carriage is operated in the following manner, on the drive being transmitted by one of the driving belts to the fast pulley 14 pinion 16—through gear wheel 18, pinion 20, and gear wheel 21—rotates sprocket wheel 23 in one direction, and the rolling carriage 6 moves along the underside of rail 3 until one of the inclined surfaces 34 meets and depresses the tappet or cam 33 at this end of the machine. As a result, spindle 28 is partially revolved so that the links 29 automatically cause lever 30 to swivel about its pivot 31 and move bar 32 when the belt which has been operating the machine is switched onto one of the loose pulley 15, and, at the same time, another belt is switched over from the other of the loose pulleys on which it has been running to the fast pulley 14. This belt rotates pulley 14 in the opposite direction, consequently, the rolling carriage 6 moves along the rail 3 in the reverse direction until the other of the inclined surfaces 34 meets and depresses the other of the tap-

pets or cams 33, when the reciprocatory operation is again repeated.

In order to vary the length of travel of the rolling carriage, said tappets or cams 33 are arranged to be fixed at any desired points 70 of the spindle slots or keyways 35.

Should it be found necessary to reverse the direction of travel of the rolling carriage 6 by hand, this may be readily effected by moving a handle lever 36 fixed to the spindle 28, 75 or by moving the lever 30 and thereby operating the belt-shifting bar 32. The carriage 6 may also be stopped by manipulating said handle lever 36 or lever 30 until the parts assume the position shown in Fig. 13 when 80 both of the driving belts will be positioned on their respective loose pulleys 15. In order to definitely place the parts in their neutral positions, there is attached to a stationary part of the machine a spring strip 37 (see 85 Fig. 14) provided with wheels or rollers 38, 38^a, wheel 38 being adapted to enter into a recess 39 of the belt-shifting bar 32 when the bar is moved in the manner just described.

Situated below the rolling carriage 6 and adapted to normally contact with roller 7 is a bed or table 40 for the reception of the material to be treated, said bed or table being formed of two sections 40^a, 40^b on the underside of each of which a rib 40^c is formed. 90 Said bed sections are connected to each other by means of springs 41, 42, said springs 41 being arranged to press against adjacent sides of said ribs 40^c and so tend to force the ribs further apart, whilst said springs 42 are positioned on the outer sides of the ribs and therefore tend to press the ribs inward towards each other so that the adjacent edges of the bed may be maintained in abutting engagement with each other. 100

Also provided on the underside of the bed 40 are a plurality of plates or buffer pieces 43 which are alternately secured to each of the sections 40^a, 40^b, as clearly shown in Figs. 2 and 3, and thereby prevent the adjacent edges of the sections riding above each other. 110

Said bed or table 40 is carried at each end by means of a bell-crank lever 44, 44^a, pivotally mounted at 45 on a stationary bracket 46, and a member 47 (see Figs. 8 and 9) provided with a fulcrum 47^a which is entered into a groove 44^b formed in the lever, and with a fulcrum 47^b which is entered into a central slot 48^a of a yoke 48 (see Figs. 6 and 7). Said yoke is formed with a pair of fulcrums 48^b each of which is entered into a slot 49^a of a block 49 (Figs. 4 and 5); said blocks are disposed in small housings 40^d formed at the ends of the sections 40^a, 40^b, of the bed. 120

Located in said housings 40^d by means of screwed studs 50 are spring washers 51 which are arranged to press on the outer sides of blocks 49 and assist the springs 42 in main- 130

taining the adjacent edges of the bed sections 40^a, 40^b in abutting engagement.

In order to normally maintain the face of bed 40 in contact with the carriage roller 7, there are provided two helical springs 52 which are located between plates 53 fitted on the end of a rod 54 and the portions 44^a of the bell-crank levers 44, 44^a. The other portions 44 of said levers are connected with an operating treadle or foot lever 55 by means of a chain 56.

When it is desired to roll a hide of leather, or the like, and assuming that carriage 6 is stationary, the treadle or foot lever 55 is depressed by the foot of the operator so that the bell-crank levers 44, 44^a swivel about their pivots 45 to compress the springs 52 and permit bed 40 to move downwardly. The material is now positioned on the bed and the pressure on the treadle lever 55 released. Thus the bed with the material is raised into contact with the carriage roller 7 under the influence of springs 52, and handle 36 or lever 30 is thereupon actuated to set carriage 6 in motion, when it reciprocates along the rail 3 in the manner hereinbefore described and the carriage roller 7 operates on the material.

It is well known that in order to carry out the rolling and finishing operation efficiently, an equal or uniform pressure must be produced over the whole surface of the material being treated, and as the hides are, as a rule, thicker in some parts than in others, suitable means must be provided so as to compensate for all inequalities of the material. With a machine as before described, the effecting of an even or uniform pressure is made possible, as the bed sections 40^a, 40^b may oscillate independently on their fulcrums 48^b against the tension and compression of springs 41, 42, whilst the bed sections may also oscillate in conjunction with each other on the central fulcrum 47^b. Thus, when the roller 7 in its travel, meets a part of the material which is of undue thickness, one or other or both of the bed sections 40^a, 40^b oscillate according to the contour of the material, so that a uniform roller pressure on the material is maintained, and, when the roller 7 has passed over the said part of the material, the bed sections are immediately returned to their original positions, as shown in Figs. 1 and 2, by the action of the springs 41, 42 on the ribs 40^c of the bed sections.

Further, said springs maintain the adjacent edges of the sections in close contact with each other during the oscillatory actions of the sections of the bed, whilst the plates or buffer pieces 43 prevent the edges of the sections riding above each other so that an unbroken joint—which cannot “bite” or nip the material—is always presented to the material during the rolling operation.

Beds so constructed are of greater width than beds formed of a single section, and are

particularly suitable for use as finishing machines, as, a longer roller can be utilized, a larger area of material can be treated in each travel of the roller, a better finish can be given to the material, the operation can be expeditiously performed, material can be more easily flattened, and the tendency for the material to raise or form mounds at those parts which lie beyond the path of the roller is reduced to a minimum.

Referring again to the bed oscillating member 47 shown in Figs. 8 and 9, it will be seen that the distance between the fulcrums 47^a, 47^b may be varied, so that the amount of lowering of the bed may be varied, as desired, to permit of materials of different thicknesses being treated. Projections 47^c are also formed on the members, which projections are entered into vertical guide slots 2^a provided in the supports 2 to keep members 47 in position.

The pressure of the bed 40 on the roller 7 may be regulated at will by adjusting the tension of springs 52 by means of a hand wheel 57 screwed on the end of rod 54. To provide means whereby the pressure being imposed on the materials may be readily ascertained, there is fixed at an end of one of the springs 52 a suitably calibrated dial 58 provided with a finger 59, and to the other end of the spring is attached a link 60 which is connected to and operates said dial finger 59.

It will be understood that I do not confine myself to the precise details as hereinbefore described, as obviously various alterations may be made without departing from the spirit and scope of the invention as defined by the claims, for instance, the bed may be formed of more than two sections, or it may be made of one section, in which case the oscillating arrangement will be suitably modified: or again, links or weighted levers may be utilized in substitution for said springs 52.

What I claim as my invention and desire to secure by Letters Patent is:—

1. In a machine of the kind specified, a work-supporting bed composed of a plurality of pivotal sections, spring means mounted on said sections to maintain the same in their normal positions and to permit individual and simultaneous pivotal movement of the sections, buffer pieces mounted on said sections to maintain adjacent edges thereof in constant abutment or contact during pivotal movement of the sections, and spring means mounted below said sections and adapted to resiliently support and maintain the work on the sections in continuous engagement with a rotary work-operating tool throughout the movement of such tool over the work.

2. In a machine of the kind specified, a work-supporting bed composed of a plurality of sections mounted upon separate pivots to

- permit individual pivotal movement of the sections and having a common pivot, means connecting the separate pivots of said sections with said common pivot to permit simultaneous pivotal movement of the sections about said common pivot, spring means mounted on said sections to maintain the same in their normal relative positions, buffer pieces mounted on said sections to maintain adjacent edges thereof in constant abutment or contact during pivotal movement of the sections, and spring means mounted below said sections and adapted to resiliently support and maintain the work on the sections in continuous engagement with a rotary work-operating tool throughout the movement of such tool over the work.
3. In a machine of the kind specified, a work-supporting bed composed of a plurality of sections mounted upon separate pivots and having a common pivot, means connecting the separate pivots of said sections with said common pivot, spring means mounted on said sections to maintain the same in their normal relative positions, buffer pieces alternately connected to the underside of said sections and projecting into engagement with the underside of adjacent sections to maintain the edges of the sections in constant abutment or contact during pivotal movement of the sections, and spring means mounted below said sections and adapted to resiliently support and maintain the work on the sections in continuous engagement with a rotary work-operating tool throughout the movement of such tool over the work.
4. In a machine of the kind specified, a work-supporting bed composed of a plurality of sections mounted upon separate pivots and having a common pivot, means connecting the separate pivots of said sections with said common pivot, flanges formed on the underside of said sections, spring means supported by said flanges on the underside of the sections to maintain the sections in their normal relative positions, buffer pieces alternately connected to the underside of said sections and projecting into engagement with the underside of adjacent sections, and spring means mounted below said sections and adapted to resiliently support and maintain the work on the sections in continuous engagement with a rotary work-operating tool throughout the movement of such tool over the work.
5. In a machine of the kind specified, a work-supporting bed composed of a plurality of sections mounted upon separate pivots and having a common pivot, means connecting the separate pivots of said sections with said common pivot, spring means supported by flanges formed on the underside of said sections to maintain the sections in their normal relative positions, buffer pieces alternately connected to the underside of said sections

and projecting into engagement with the underside of adjacent sections, bell-crank levers mounted to support the common pivot of said sections, and helical springs mounted to bear on said bell-crank levers and to exert upward yieldable pressure on the bed or table sections, whereby to maintain the work on the sections in continuous engagement with a rotary work-operating tool throughout the movement of such tool over the work.

6. In a machine of the kind specified, a work-supporting bed composed of a plurality of sections mounted upon separate pivots and having a common pivot, means connecting the separate pivots of said sections with said common pivot, spring means supported by flanges formed on the underside of said sections to maintain the sections in their normal relative positions, buffer pieces alternately connected to the underside of said sections and projecting into engagement with the underside of adjacent sections, bell-crank levers mounted to support the common pivot of said sections, helical springs mounted to bear on said bell-crank levers and to exert upward yieldable pressure on the bed or table sections, whereby to maintain the work on the sections in continuous engagement with a rotary work-operating tool throughout the movement of such tool over the work, a pressure indicating mechanism connected with one of said bell crank levers to indicate the resilient upward pressure of said springs on said bed sections, and means for varying the pressure of the springs on said sections.

In testimony whereof I affix my signature.
